PROCESS OF FORMING AND UTILIZING CHARGES IN COMBUSTION-MOTORS.

1,320,500.

Specification of Letters Patent.

Patented Nov. 4, 1919.

Application filed April 16, 1915. Serial No. 21,876.

To all whom it may concern:

Be it known that I, JOHN A. SECOR, a citizen of the United States, residing at Laporte, in the county of Laporte and State 5 of Indiana, have invented a certain new and useful Improvement in Processes of Forming and Utilizing Charges in Combustion-Motors, of which the following is a specification.

10 My invention relates to improvements in processes of forming and utilizing a charge in a combustion motor, and has for one object to provide a new and improved process for the operation of a combustion engine on 15 low grade liquid fuels, wherein will be obtained those advantages heretofore confined to "throttling" engines in which combustion occurs at constant volume with an increase of internal pressure. These advantages 20 include moderate weight of power unit and cost of manufacture; high efficiency, both mechanical and commercial; flexibility, including adaptability for high piston speeds and rotation rates. Added to these 25 advantages, an engine operating under this process will have the thermal efficiency of the high compression, constant combustion pressure oil engine.

It is well known that, when a charge of 30 air is drawn into the cylinder of a combustion engine, and is then compressed, the pressure may become so great that the heat of compression will be sufficient without any other ignition means to ignite or fire the 35 charge of fuel, and the so-called Diesel motor is one of the best known motors operating under this principle. In such a motor, special means are provided for injecting the fuel into the combustion chamber, because to prevent pre-ignition the fuel 40 is not injected appreciably until the beginning of the power stroke. This necessitates means for developing a pressure greater than the compression and combustion pressure of the engine for forcing the oil fuel in against that pressure. The oil fuel is fed into the cylinder at such a rate that the expansion due to the heat of combustion keeps pace with the increase of volumetric capacity 45 due to the movement of the piston, so that the pressure within the cylinder remains substantially unchanged until the fuel supply is cut off by the governor, following which adiabatic expansion ensues and is accompanied by falling pressure to the com-

pletion of the working stroke in the usual manner.

In this arrangement, the fuel is injected and burned gradually, being mixed with the air only as it burns, and the longer the burning continues the less freely does it take place owing to the natural decrease in the relative proportion of oxygen, that is to say, the oil or fuel which is injected into the chamber burns slowly in the form of a continuous jet of flame because it is not intermingled with the air, as in the usual gas engine practice, and only that air which comes in actual contact with the oil fuel is available for combustion. This results in slowing 65 down the combustion and compelling the motor to operate at low speeds otherwise there is no time for combustion to take place or for the fuel to enter in.

The above must be contrasted with the 75 ordinary combustion motor wherein the air and fuel are mixed and commingled before ignition so that each fuel particle is surrounded by its proper oxygen supply, thus permitting an almost instantaneous combustion 80 of the charge extending throughout the entire combustion chamber, thus insuring the complete ignition under constant volume at the beginning of the stroke and allowing expansion to do the work from then on. 85 This of course permits higher speeds, and is one of the radical differences in performance between the high compression, slow burning constant pressure motor and the low compression constant volume explosion 90 motor as now in use. In my arrangement I propose to combine certain features of the low compression constant volume motor with the thermal advantages of constant high compression at all loads and speeds. 95

My engine then is somewhat similar to the Diesel in that constant high compressions are used for a varying output of power, and that high temperatures are developed in the combustion chamber by the compression employed. I propose to compel the air as it is inhaled uncontrolled and unthrottled during the suction stroke, to inhale with it the proper fuel supply, thus insuring a mixing 100 and commingling of the atomized fuel with the air, and rendering separate fuel injecting means, and fuel valves exposed to the heat and pressure of the compression and explosion pressures unnecessary. I propose, however, to add to the mixture a supply of 105 110

water or other suitable combustion retarding or cylinder cooling means such as will prevent self-ignition. At the appropriate time I will then fire the charge with an electric spark in the usual manner.

The admixture of water with the fuel charge forms a fuel mixture of high specific heat, reducing the tendency to self-ignition at high loads and permitting higher compression, and if enough water is used the temperature may be held down to any desired point. The amount of water and the amount of fuel may be varied. The quantity of air is always practically uniform, thus the volume of mixture entering is always the same, but it varies in richness, and the power output of the engine is controlled by varying in thermal coordination the relative quantities of fuel and water. A full unthrottled air charge is thus inhaled at every charging stroke, as in Brayton or Diesel oil engines, or ordinary "hit or miss" governed gas engines. It differs from the Diesel in that fuel and water are atomized by the entering air charge, being commingled therewith and inhaled as constituents of a homogeneous fuel charge, thereby obviating the mechanical power loss involved by fuel injection under pressure in excess of the pressure of compression and combustion. It still further differs from the Siemens, Brayton and Diesel engines in that combustion occurs at constant volume and not under constant pressure.

The supply of fuel and water is positively turned on and off in a pre-determined synchronous relation to the movement of the engine intake valve, and is so timed that the fluid is turned off always except during that portion of the air intake stroke when the air velocity is at or near a maximum, thus all drooling and dripping and leaking or seepage of the fuel and water from the supply nozzles at inopportune times is prevented, and only that amount of water or oil permitted to enter which is desired, and then only at the time when conditions are such that a maximum atomizing effect is obtained. A governor is provided which varies the quantity of fuel fed by controlling the effective size of the liquid supply pipe to control the speed and power, and this governor controls only the fuel and water, the air supply being always the same, the amount of air entering the cylinder for each stroke being the same, no matter what the speed or power.

My engine, therefore, takes in a constant volume of combustible mixture at each stroke. The mixture may be rich or it may be lean; it may have a maximum or it may have a minimum of fuel but it is constant in volume. All the air passes through the Venturi tube and thus the problem of adjusting the relation between the engine and

air and liquid is simple because there are no variable intakes, no throttle valves and no other interfering elements to enter in and the air velocity through the Venturi tube is in direct relation to the speed of the piston. I use a Venturi tube through which the air is drawn merely for the purpose of insuring maximum velocities of air and thus a maximum of atomization and mixing. Under some circumstances it might be desirable to dispense with the Venturi tube and use other arrangement of intakes.

My invention is illustrated more or less diagrammatically in the accompanying drawings, wherein—

Figure 1 is a section showing an engine cylinder and air passage;

Fig. 2 is a section on the line 2—2 of Fig. 1;

Fig. 3 is a detail of the controlling valve; and

Fig. 4 is a detail section on the line 4—4 of Fig. 2.

Like parts are indicated by like letters throughout the several figures.

A is an engine cylinder, A¹ the cooling jacket; A² the piston; A³ a cam shaft carrying a cam A⁴; A⁵ a cam roller; A⁶ a valve stem carrying the cam roller; A⁷ an air inlet valve; A⁸ the valve seat; A⁹ the air supply passage bounded at one end with the valve seat A⁸ and at the other end by the Venturi tube A¹⁰.

B, C are oil and water supply pipes discharging into the Venturi tube at its smallest point. They are each of them controlled by valves B¹, C¹ having adjustable lever arms B², C² controlled by links B³, C³ which in turn are adjustably mounted on the lever arms B⁴, C⁴ on the governor controlled rock shaft D. This governor controlled rock shaft has a rocker arm D¹ on which is pivoted one end of the link D², the other end of which leads to a sliding sleeve D³ controlled by governor weights D⁴ in the usual manner. These governor weights are rotated through the intermedium of the miter gears D⁵ in response to the rotation of the engine. D⁶ is a collar on the shaft D. In it is a pin D⁷. It is held in adjustable position upon that shaft by the set screw D⁸ so that play may be had between the governor and the lug B⁴⁰ on the hub which carries the arm B⁴, thus permitting adjustment of the water and oil for different responses to the governor when desirable, so that the water will be shut off as the load decreases before the fuel is completely shut off. The pipes B, C are also controlled by valves B⁵, C⁵. These valves are adapted to open and shut positively and they are controlled by operating levers B⁶, C⁶ on which at adjustable points are pivoted the links B⁷, C⁷ which links are in turn controlled and pivoted at the other end of the rock shafts B⁸, C⁸ on the rock

shaft E. The distance between the pivotal point of either end of said links and the axis of rotation is adjustable. E¹ is a lever on the rock shaft E. It is slotted to engage 5 the pin E² on the valve stem A⁶ so that a movement up and down of the valve stem results in a rotary movement of the valves B⁵, C⁶. These valves, as indicated, are of such size and shape that the valve cylinder 10 B⁹ makes an appreciable rotation before the aperture therethrough comes in line with the fuel line. The result is that the valve is closed at the beginning and at the end of the intake stroke and it is only during 15 the mid part of the intake stroke when the puppet valve of the engine is wide open and the intake velocity is a maximum that oil or water is fed to the air. The lever E¹ and the lever B⁸ have what is in effect a 20 bell crank lever and for convenience I have so termed the combination.

F is a spark plug to which leads an ignition wire fed with a current from any suitable means not here shown and controlled 25 in any suitable manner not forming a part of my invention.

It will be evident that while I have shown in my drawings an operative device still many changes might be made both in size, 30 shape and arrangement of parts without departing from the spirit of my invention and I wish, therefore, that my drawings be regarded as in a sense diagrammatic.

The use and operation of my invention 35 are as follows:—

In the drawings the parts are shown at the beginning of the suction stroke. The piston is about to descend, and the intake valve about to rise. When it rises, the intake 40 valve stem will rotate the bell crank lever pinned thereto and thus will rotate the liquid cut off valve levers to open the water and fuel valve. When this opening has occurred, the engine intake valve will 45 have had time to open sufficiently to insure the passage of a high velocity stream of air through the Venturi tube past the engine valve into the cylinder.

It will be noted that in the diagrammatic 50 form which I have shown, the liquid control valves are plug valves, and that an appreciable angular movement of the valve must take place before the liquid can commence to pass through. It is this angular movement which gives time for the engine intake valve to open wide before the liquid oil or water is permitted to flow, and it is this delay which insures a high velocity current of air before any oil or water is 55 fed, and also the picking up and carrying on or atomization of all fuel and water discharged toward the Venturi tube.

The interval during which the supply of fuel and water is permitted I call the mid 60 stroke and the cutting in and cutting out

of these valves is effected near the ends of the stroke, but only during such mid stroke.

As the intake valve commences to descend at the end of the suction stroke, it will rotate the bell crank lever in the opposite 70 direction to shut off the fuel and water valves, and these valves will both be closed appreciably before the closure of the intake valve, thus insuring a continuance of the high velocity air current long enough to take up, atomize, mix and carry into the cylinder all of the water and fuel which may have been delivered by the water and fuel valves to the Venturi tube. The fuel and water 80 valves controlled in direct operative relation to the rotation of the engine are always open for exactly the same length of time during each suction stroke. They positively shut off the fuel and water supply 85 at all times except during the suction stroke, and they are open always for the same proportion of the suction stroke. They cannot therefore control the amount of fuel or water fed to the engine, because they always 90 are open wide for a fixed time interval. In order to control the amount of liquid fed at each stroke, I provide a valve between each positive cut off valve and its discharge nozzle, and each of these valves is controlled by the governor, the governor being driven in the usual manner by the engine to operate these valves to open or shut them as the case may be, and thus control the amount of fuel or water which can be fed into the 95 Venturi tube during the time when the liquid supply is open by the direct engine controlled valve.

In order that the relative amounts of fuel and water may be properly adjusted, I 100 provide the usual arrangement of slotted levers and screw held connecting rods, and in addition I provide an adjustable sleeve and pin as indicated, so that one valve may be set for operation after the other, so that 105 the water valve will be operated before the oil valve, thus permitting an entire elimination of the water supply at low loads.

The result of so operating is, that there 110 will be a very thorough and positive atomization and mixing of fuel and water with the air due to the high velocity and large volume of the air current flowing into the cylinder. This thorough atomization of the fuel permits the use in the cylinder of high compression without self-ignition, so that 115 the cylinder may, for example, in connection with the use of low grade liquid fuels, have compression of say 100 pounds, although this figure is used merely for the matter of illustration. By in like manner thoroughly atomizing the water, which, by 120 cooling the interior of the cylinder, has a retarding effect of ignition, it is possible to still further increase the compression in 125

the cylinder to say, for example, 200 pounds without self-ignition. Of course, both of these results could be more or less secured by leading less than all of the air through 5 the Venturi tube into which it goes but this is obviously the preferred form of the structure. The compression in the cylinder can be increased in proportion to the thoroughness of the atomization of the liquid 10 fuel, and again in proportion to the thoroughness of the atomization of the water, and by my arrangement the atomization of both can be carried to a point where the compression in the cylinder can be as high 15 as is consistent with economic structure arrangements. Thus the preferred process involves the taking of the entire air supply through the passageway into which the fuel and water are discharged, and the discharge 20 of fuel and water during only the mid-stroke.

The term "high compression" is, of course, relative, and moreover in designing an engine, many of the important features of 25 my invention could be conserved without having a positively high compression. In such case, however, there would always be a constant compression pressure. If, therefore, in any given case, a designer wishes 30 to use my invention, and dispense with the advantages incident to so-called high compression pressure, he may still secure the benefit of a constant compression pressure, because he will have a uniform and 35 uncontrolled supply of air. By having this uncontrolled air supply and feeding the fuel or water, or both, in the manner proposed, he will get a constant compression pressure even at low pressures, and thus a high ther- 40 modynamic efficiency at low loads.

The arrangement can be such that either or both fuel and water can be thus introduced into a constant compression pressure cylinder when such pressure is either high 45 or low, but preferably when it is high.

In order to make the foregoing description and the following claims clearly intelligible as to meaning and scope, it seemed best to explain the significance which I at- 50 tach to certain words and expressions.

Where I have spoken of "constant compression", "constant volume", "constant quantity" and "uniform quantities" and the like, I mean, of course, to use these terms as 55 if they were preceded by the word "approximately". Where I speak of "uniform quantities" I mean to distinguish between the approximately uniform quantities as they are for example utilized in my process 60 where there is no throttling of the air, and the sharply varying successive quantities of air taken into a cylinder where the operation involves the use of air throttling.

When I use the expression "constant com- 65 pression", I mean thereby to indicate ap-

proximately a condition such as that which prevails in the Diesel engine.

By the use of the term "compression stroke", I mean the stroke of the piston during which the charge is compressed in the 70 cylinder.

By the expression "self ignition" I mean, of course, such ignition as takes place, for example, in the Diesel engine, or in any engine wherein ignition comes from the heat 75 of compression.

By the term "ignition" not so modified or limited I mean, of course, ignition by separate means or means other than heat of compression. 80

By the expression "water" I, of course, mean water in any of its various forms.

By the expression "self ignition preventive" I mean any substance which applied or mixed with the charge will tend to delay or 85 prevent self-ignition.

I claim:—

1. The process of forming and utilizing the charge in a combustion motor which consists in supplying air to the cylinder 90 thereof, then while continuing the supply of air supplying liquid fuel thereto and atomizing it, then discontinuing the supply of fuel but continuing the supply of air until the cylinder is sufficiently supplied 95 with the desired mixture.

2. The process of forming and utilizing the charge in a combustion motor which consists in supplying air to the cylinder thereof, then while continuing the supply 100 of air supplying liquid fuel and a liquid pre-ignition preventive thereto and atomizing them, then discontinuing the supply of fuel and such pre-ignition preventive but continuing the supply of air until the cylinder 105 is sufficiently supplied with the desired mixture.

3. The process of forming and utilizing the charge in a combustion motor which consists in supplying air to the cylinder 110 thereof, then while continuing the supply of air supplying liquid fuel and water thereto and atomizing them, then discontinuing the supply of fuel and water but continuing the supply of air until the cylinder is 115 sufficiently supplied with the desired mixture.

4. The process of forming and utilizing the charge in a combustion motor which consists in supplying air to the cylinder there- 120 of, then while continuing the supply of air supplying successively fuel and water thereto, then discontinuing the supply of fuel and water but continuing the supply of air until the cylinder is 125 sufficiently supplied with the desired mixture.

5. The process of forming and utilizing the charge in a combustion motor which consists in supplying air to the cylinder thereof by a current having a high velocity 130.

- zone and period, then while continuing the supply of air supplying liquid fuel to such current at such high velocity zone by inhalation due to the air current while at its 5 approximate maximum velocity, then discontinuing the supply of fuel but continuing the supply of air until the cylinder is sufficiently supplied with the desired mixture.
- 10 6. The process of forming and utilizing the charge in a combustion motor which consists in supplying air to the cylinder thereof by a current having a high velocity zone and period, then while continuing the 15 supply of air supplying liquid fuel and a liquid pre-ignition preventive by inhalation due to the air current while at its approximate maximum velocity, then discontinuing the supply of fuel and such pre-ignition preventive but continuing the supply of air until the cylinder is sufficiently supplied with the desired mixture.
7. The process of forming and utilizing the charge in a combustion motor which 25 consists in supplying air to the cylinder thereof by a current having a high velocity zone and period, then while continuing the supply of air supplying fuel and water to such current, then discontinuing the supply 30 of fuel and water, but continuing the supply of air until the cylinder is sufficiently supplied with the desired mixture.
8. The process of forming and utilizing the charge in a combustion motor which 35 consists in supplying air to the cylinder thereof by a current having a high velocity zone and period, then while continuing the supply of air supplying liquid fuel to such current within such high velocity zone and 40 during such high velocity period by inhalation due to the air current while at its approximate maximum velocity, then discontinuing the supply of fuel but continuing the supply of air until the cylinder is sufficiently supplied with the desired mixture.
- 45 9. The process of forming and utilizing the charge in a combustion motor which consists in supplying air to the cylinder thereof by a current having a high velocity zone and 50 period, then while continuing the supply of air supplying liquid fuel and a pre-ignition preventive to the current within such high velocity zone during such high velocity period, then discontinuing the supply of fuel 55 and such pre-ignition preventive but continuing the supply of air until the cylinder is supplied with the desired mixture and then igniting such charge.
10. The process of forming and utilizing the charge in a combustion motor which 60 consists in supplying air to the cylinder thereof by a current having a high velocity zone and period, then while continuing the supply of air supplying fuel and water to such current 65 within such high velocity zone and during such high velocity period, then discontinuing the supply of fuel and water but continuing the supply of air until the cylinder is sufficiently supplied with the desired mixture and independent of the compression 70 pressure thereof.
11. The process of forming and utilizing the charge in a combustion motor which consists in supplying air to the cylinder thereof, 75 then while continuing the supply of air supplying liquid fuel thereto and atomizing them, then discontinuing the supply of fuel but continuing the supply of air until the cylinder is sufficiently supplied with the desired mixture and then igniting such charge 80 independent of the compression pressure thereof.
12. The process of forming and utilizing the charge in a combustion motor which consists in supplying air to the cylinder thereof, 85 then while continuing the supply of air supplying successively fuel and water thereto, then discontinuing the supply of fuel and water but continuing the supply of air until the cylinder is sufficiently supplied with the desired mixture and then igniting such charge 90 independent of the compression.
13. The process of forming and utilizing the charge in a combustion motor which consists in supplying air to the cylinder thereof 95 by a current having a high velocity zone, then while continuing the supply of air supplying liquid fuel and a liquid pre-ignition preventive, by inhalation due to the air current while at its approximate maximum velocity, then discontinuing the supply of fuel and such pre-ignition preventive but continuing the supply of air until the cylinder is sufficiently supplied with the desired mixture and then igniting such charge 100 independent of the compression.
14. The process of forming and utilizing the charge in a combustion motor which consists in supplying air to the cylinder thereof by a current having a high velocity zone 110 and period, then while continuing the supply of air supplying fuel and water and a pre-ignition preventive, then discontinuing the supply of fuel and water and such pre-ignition preventive but continuing the supply of air until the cylinder is sufficiently supplied with the desired mixture and then igniting such charge 115 independent of the compression.
15. The process of forming and utilizing the charge in a combustion motor which consists in supplying air to the cylinder thereof by a current having a high velocity zone and period, then while continuing the supply of air supplying fuel and water to such current, 120 then discontinuing the supply of fuel and water, but continuing the supply of air until the cylinder is sufficiently supplied with the desired mixture and then igniting such charge 125 independent of the compression.
16. The process of forming and utilizing the charge in a combustion motor which consists in supplying air to the cylinder thereof by a current having a high velocity zone and period, then while continuing the supply of air supplying fuel and water to such current, 130 then discontinuing the supply of fuel and water, but continuing the supply of air until the cylinder is sufficiently supplied with the desired mixture and then igniting such charge independent of the compression.

16. The process of forming and utilizing the charge in a combustion motor which consists in supplying air to the cylinder thereof by a current having a high velocity zone and period, then while continuing the supply of air supplying liquid fuel to such current within such high velocity zone and during such high velocity period, by inhalation due to the air current while at its approximate maximum velocity, then discontinuing the supply of fuel but continuing the supply of air until the cylinder is sufficiently supplied with the desired mixture and then igniting such charge independent of the compression.
17. The process of forming and utilizing the charge in a combustion motor which consists in supplying air to the cylinder thereof by a current having a high velocity zone and period, then while continuing the supply of air supplying liquid fuel and a liquid pre-ignition preventive to the current within such high velocity zone during such high velocity period, by inhalation due to the air current while at its approximate maximum velocity, then discontinuing the supply of fuel and such pre-ignition preventive but continuing the supply of air until the cylinder is supplied with the desired mixture and then igniting such charge by externally controlled means.
18. The process of forming and utilizing the charge in a combustion motor which con-

sists in supplying air to the cylinder thereof by a current having a high velocity zone and period, then while continuing the supply of air supplying fuel and water to such current within such high velocity zone and during such high velocity period, then discontinuing the supply of fuel and water but continuing the supply of air until the cylinder is sufficiently supplied with the desired mixture and then igniting such charge by externally controlled means.

19. The process of forming and utilizing the charge in a combustion motor which consists in supplying air to the cylinder thereof by a current having a high velocity zone, then while continuing the supply of air supplying fuel to such current at such zone, by inhalation due to the air current while at its approximate maximum velocity, then discontinuing the supply of liquid fuel but continuing the supply of air until the cylinder is sufficiently supplied with the desired mixture and then igniting such charge independent of the compression.

In testimony whereof I affix my signature in the presence of two witnesses this 13th day of April, 1915.
